UNITED STATES PATENT OFFICE.

JOHN H. KILLION, OF CHICAGO, ILLINOIS.

CONTAINER.

Application filed July 2, 1921. Serial No. 482,023.

To all whom it may concern:

Be it known that I, JOHN H. KILLION, a citizen of the United States, residing at 1628 Prairie Avenue, Chicago, in the county of Cook and State of Illinois, have invented a new and useful Improvement in Containers, of which the following is a specification.

This invention relates to containers and is fully described in the following specification and shown in the accompanying drawings, in which Figure 1 is a plan view of the container, Fig. 2 is a side elevation of the same, Fig. 3 is a partial section on the line 3 of Fig. 2, Fig. 4 is a partial perspective of the edge of the barrel showing the edges to be joined, Fig. 5 is a partial perspective of the closing member and Fig. 6 is a partial section on the line 6 of Fig. 2.

The barrel 10 of this container consists of a sheet of metal, fibre board or other suitable material bent into the form of a cylinder and having edges meeting upon a longitudinal line, said edges being bent back to form reversely extending lips 11 as shown in Fig. 4.

The closing member 12, having a longitudinal opening 13, is adapted to slide endwise over the lips 11 so as to retain them against separation and against lateral movement. An ear 14 is formed on the end of this member which may be bent over the end of the barrel, as shown in Fig. 6, to retain it thereon.

A head 15 lies within the barrel 10 and has an angular flange 16 which passes around and over the outer edge of the barrel. This head may be retained in the barrel by means of tongues 17 which are pressed inwardly from portions of the flange and barrel, and each of sufficient stiffness to retain the head on the barrel.

The present invention is concerned only with so much of the foregoing structure as relates to the means for forming a closing 45 on the barrel 10, the means for retaining the head upon the barrel being covered by my accompanying application, Serial No. 482,022, filed July 2, 1921.

While I have shown and described but 50 a single embodiment of my invention it is to be understood that it is capable of many modifications. Changes therefore in the construction and arrangement may be made without departing from the spirit and scope 55 of the invention as disclosed in the appended claims, in which it is my intention to claim all novelty inherent in my invention as broadly as possible in view of the prior art.

What I claim as new and desire to secure by Letters Patent, is:

1. In a container, a hollow barrel formed from a sheet, the ends of the sheet meeting on a longitudinal line, said ends reversely facing from said line, a member slidable 65 longitudinally over said ends, the ends of said barrel being substantially cylindrical, a head for said container and means for retaining the head therein including an integral flange passing over the edge of said 70 barrel, said flange retaining said member against endwise movement.

2. In a container, a hollow barrel formed from a sheet, the ends of the sheet meeting on a longitudinal line, said ends reversely facing from said line, a member slidable 75 longitudinally over said ends, a head for said container and means for retaining the head therein including a flange integral with said head passing over the edge of said 80 barrel, said flange enclosing the end of said member so as to retain it against endwise movement.

JOHN H. KILLION.
